OUTDOOR LIGHTING FIXTURE

Albert E. Brooks, Harold A. Bacon, and Theodore H. Stark, Stockton, Calif., assignors to Electric Lighting, Inc., Stockton, Calif., a corporation of California

Application August 6, 1951, Serial No. 16,174

Term of patent 14 years

(Cl. D48—31)

To all whom it may concern:

Be it known that we, Albert E. Brooks, Harold A. Bacon, and Theodore H. Stark, citizens of the United States, residing at Stockton, in the county of San Joaquin and State of California, have invented a new, original, and ornamental Design for Outdoor Lighting Fixture, of which the following is a specification, reference being had to the accompanying drawing, forming a part thereof.

Fig. 1 is a bottom perspective view of an outdoor lighting fixture, showing our new design.

Fig. 2 is a top plan view of the fixture.

Fig. 3 is a fragmentary cross sectional view taken on line 3—3 of Fig. 1.

We claim:

The ornamental design for an outdoor lighting fixture, as shown.

ALBERT E. BROOKS.
HAROLD A. BACON.
THEODORE H. STARK.
